FORCE TRANSMISSION APPARATUS

Hale G. Zimmerman, San Jose, Calif., assignor to International Business Machines Corporation, New York, N. Y., a corporation of New York

Application December 21, 1953, Serial No. 399,385

12 Claims. (Cl. 74—128)

This invention relates generally to apparatus for mechanically transmitting force, and more particularly to force transmission means in which a flexible element is stiffened to enable transmission of the force through the flexible element.

The principal object of this invention is to provide a new and improved force transmission apparatus for actuation at high speed.

In order for an apparatus to achieve high speed actuation, the component parts must have a small mass; the distances through which the parts move must be small, and a large actuating force must be developed by the parts. The apparatus of the present invention utilizes these factors to obtain high speed actuation.

Other objects of the invention will be pointed out in the following description and claims and illustrated in the accompanying drawings, which disclose, by way of examples, the principle of the invention and the best mode, which has been contemplated, of applying that principle.

In the drawings:

Fig. 1 is a side view partly in section of one embodiment of the invention showing the parts in an inoperative position.

Fig. 2 is a view similar to Fig. 1 showing the parts in an operative position.

Fig. 3 is a side view partly in section of another embodiment of the invention.

Fig. 4 is a side view partly in section of still another embodiment of the invention.

Referring to Figs. 1 and 2 of the drawings, the embodiment of the invention illustrated comprises an elongated flexible transmitting means 10, preferably in the form of a resilient magnetizable column or wire, intended for transmitting force from one end to the other, and of such character as to require the use of a means intermediate its ends to prevent buckling during operation.

Wire 10 is secured at one end to an operating arm 11 at 12. The arm 11 is pivotally mounted at 13 and is provided with a roller 14 which is held against a constantly rotating cam 15 under pressure of a spring 16. Cam 14 is fastened to a shaft 17 which is connected to any suitable driving mechanism to continually rotate the shaft.

The other end of wire 10 is secured to a punch element 18 which is slidably mounted in a stripper plate 19. A die block 20 is positioned below the stripper plate at a suitable distance to permit cards or sheets to be inserted therebetween. This may be done by conventional card or sheet feeding means or by hand if so desired. A friction damping device generally designated 21 is mounted above stripper plate 19 and is adapted to receive the punch element 18. The damping device 21 comprises a housing block member 22 which is formed with a vertical opening 23 through which the punch element 18 is free to move and a longitudinally disposed hollowed-out portion 24 which merges with the vertical opening 23. A plunger 25 is positioned for movement

within the portion 23 and is urged into engagement with punch element 18 under pressure of a spring 26 which extends between plunger 25 and a stop member 27 secured to the end of an adjusting screw 28. This screw 5 extends into the hollowed-out portion 24 and is utilized to regulate the pressure of plunger 25 against the punch element 18.

A guide plate 29 of non-magnetic material is positioned between the operating arm 11 and the punch element 18 so that wire 11 lays flat against the guide plate when in the normal inoperative position, as shown by the full line in Fig. 1. Centrally located in the guide plate 29 is an opening 30 in which is mounted a U-shaped core 31 of a magnet 32. A coil 55 is wound around the body portion of the core 31. The ends of the core 31 are positioned flush with the face of guide plate 29. When magnet 32 is energized, the core 31 is magnetized and attracts the wire 10.

In the punching embodiment of the invention illustrated in Fig. 1, the wire 10 is shown in a full line in the normal inoperative position where roller 14 is riding in a low portion of cam 15 and operating arm 11 is pivoted upwardly. To place the apparatus in operating order, the adjusting screw 28 is turned into the hollowed-out portion 24 of the friction damping device 21 until the proper pressure is applied on the punch element 18 by plunger 25. Magnet 32 is then energized, and its core 31 becomes magnetized to develop a magnetomotive force sufficient to hold the wire 10 flat against the guide plate 29. This magnet 32 is energized through any suitable circuit; for example, in Fig. 1 depression of the key SK closes its contacts 33 to complete a circuit to magnet 32 from battery 34. When the roller 14 reaches a high portion of cam 15, the wire 10 is moved downwardly by operating arm 11. The magnetomotive force of the magnet 32 is sufficient to maintain the wire 10 against the guide plate 29 and overcome the friction developed by the friction damping device 21. Any buckling of the wire 10 is thereby prevented, and the punch element 18 is pushed downwardly through the die block 20 to accomplish the punching operation as shown in Fig. 2. When roller 14 leaves the high portion of cam 15, the punch element 18 and wire 10 are restored from the fully down position to the fully up position. The apparatus 35 is then ready to begin the next cycle of operation. If the magnet 32 is not energized, the downward movement of operating arm 11 does not cause the wire 10 to move downwardly with it, but rather buckles the wire out and away from the guide plate 29 to the position shown by the dotted line in Fig. 1. The stiffness or rigidity of the wire is not sufficient to overcome the force of friction developed by the friction damping device 21 since there is no magnetomotive force to hold the wire flat against the guide plate 29.

In Fig. 3, a modification of the invention is shown involving the application of the force transmitting principle to the actuation of a stepping device such as a counter.

A wire 10a is connected to an operating arm (not shown) which functions in the same manner as operating arm 14 in the punching embodiment described above. The lower end of wire 10a is secured to a link 35 which is slidably mounted in a friction damping device generally designated 21a similar to the one previously described for the embodiment of Figs. 1 and 2. This device 21a comprises a block member 22a which is formed with a vertical opening 23a through which link 35 is free to move and a longitudinally disposed hollowed-out portion 24a which merges with the vertical opening 23a. A plunger 25a is positioned for movement within the portion 23a and is urged into engagement with link 35 under pressure of a spring 26a which extends between plunger 25a and a stop member 27a secured to the end of an

adjusting screw 28a. This screw extends into the hollowed-out portion 24a and is utilized to regulate the pressure of plunger 25a against the link 35.

A pawl 36 is pivotally connected to the lower end of links 35 and 37 and cooperates with a counting device, generally designated 38, to effect a readout of desired information. The counting device 38 comprises a ratchet wheel 39 secured to a shaft 40 which is suitably mounted for rotation. A disc 41 is fastened to shaft 40 and carries a wire 42 having wiping brushes 43 positioned 180° apart. This counting mechanism is associated with a settable digit representing element or readout means comprising an insulating ring 44, ten contact pins 45 spaced at 18° intervals, and a common segment 46. A contact pin 45 is engaged by one brush 43, while the oppositely disposed brush 43 engages the common segment 46 to complete a circuit through the contact wire 42 between a contact pin 45 and the common segment. A spring 47 continually urges the pawl 36 toward engagement with the ratchet wheel 39. A stop pin 48 is provided in the path of pawl 36 to limit the clockwise movement of the pawl under influence of spring 47.

A guide plate 29a and magnet 32a are provided as for the previous embodiment. The core 31a of magnet 32a is mounted in a centrally located opening 30a in guide plate 29a. When magnet 32a is energized, the core 31a is magnetized and attracts the wire 10a.

In the counter embodiment of Fig. 3, the wire 10a is shown in a full line in the normal inoperative position. Energization of magnet 32a causes core 31a to become magnetized and develop a magnetomotive force sufficient to hold the wire 10a flat against the guide plate 29a. The magnet is energized through any suitable circuit, as explained hereinbefore. A downward movement by the operating arm pushes wire 10a downwardly because the magnetomotive force of magnet 32a is sufficient to maintain wire 10a against the guide plate 29a and overcome the friction developed by the friction damping device 21a. The link 35 is pushed downwardly, and pawl 36 moves with the link to push a tooth of the ratchet wheel 39 before it, thus rotating the wheel one step in a clockwise direction. When the operating arm again moves upwardly, the link 35 and wire 10a are restored, and the pawl 36 snaps over the next higher tooth on ratchet wheel 39. If the magnet 32a is not energized, the downward movement of the operating arm causes the wire 10a to buckle out and away from the guide plate 29a to the position shown by the dotted line in Fig. 3.

In Fig. 4, a modification of the invention is shown involving the application of the force transmitting principle to the actuation of a printing device.

A wire 10b is connected to an operating arm (not shown) which functions in the same manner as the operating arm 14 in Fig. 1. The lower end of wire 10b is secured to a type carrier 50 which is slidably mounted in a friction damping device generally designated 21b similar to the ones previously described. This device 21b includes a block member 22b having a vertical opening 23b through which type carrier 50 is free to move and a longitudinally disposed hollowed-out portion 24b. A plunger 25b is positioned for movement within the portion 23b and is urged into engagement with type carrier 50 under pressure of a spring 26b which extends between plunger 25b and a stop member 27b secured to the end of an adjusting screw 28b. This screw is utilized to regulate the pressure of plunger 25b against the type carrier 50.

A print platen 51 is fixed below the friction damping device 21b at a suitable distance to permit cards or sheets to be inserted therebetween. A type element 52 is mounted to the lower end of the type carrier 50 and cooperates with a ribbon 53 to print the desired impression. A card 54 is shown in place in Fig. 4 to receive a printing impression.

A guide plate 29b and magnet 32b are provided as

for the previous embodiment. The core 31b of magnet 32b is mounted in a centrally located opening 30b in guide plate 29b. When magnet 32b is energized, the core 31b is magnetized and attracts the wire 10b.

In the printing embodiment of Fig. 4, the wire 10b is shown in a full line in the normal inoperative position. Energization of magnet 32b causes the wire 10b to be held flat against the guide plate 29b as before. When the type carrier 50 is pushed downwardly by the wire 10b through the downward movement of the operating arm, the type element 52 is moved against the ribbon and the card 54 which is supported by the platen 51. A printing impression is left on the card 54 through the impact. When the operating arm again moves upwardly, the type carrier 50 and wire 10b are restored. If the magnet 32b is not energized, the downward movement of the operating arm causes wire 10b to buckle out and away from the guide plate 29b to the position shown by the dotted line in Fig. 4.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. A mechanism for transmitting force comprising in combination a flexible element, a first member mounted in forced transmitting relationship with one end of said element and operable to provide a predetermined force thereto, a second member mounted in motion receiving relationship with the opposite end of said element, means including electromagnetic means selectively operable to render said flexible element rigid to cause said second member to be moved by said element in accordance with the said predetermined force, and damping means associated with said second member for resisting movement of said second member until said electromagnetic means is operated.
2. The combination recited in claim 1 wherein said second member comprises a punch member.
3. A mechanism comprising force transmitting means including a flexible element, a damping device cooperating with said transmitting means to resist transmission of force thereby, means for stiffening said flexible element, and means for making said transmitting means effective to transmit force against the action of said damping device after said element has been stiffened.
4. The mechanism as claimed in claim 3, wherein the damping device frictionally engages the transmitting means.
5. The mechanism as claimed in claim 3, in which the stiffening means includes a magnet for holding the flexible element rigid.
6. The mechanism as claimed in claim 3, in which the damping device includes a housing block having an opening into which the transmitting means extends and a plunger member for holding said transmitting means in frictional engagement with the side of said opening.
7. The mechanism as claimed in claim 6, in which resilient means is provided between the plunger member and the housing block to yieldably hold the transmitting means against the side of the opening.
8. The mechanism as claimed in claim 7, in which an adjustable screw is interposed between the resilient means and the housing block to regulate the pressure of the plunger member against the transmitting means.
9. A force transmitting mechanism comprising a force transmitting means including a flexible element, a damping device cooperating with the transmitting means, to resist transmission of force thereby, a guide plate against which said element rests when in an unflexed position, a

magnet for holding said element rigid, and means for making said transmitting means effective to transmit force against the action of said damping device after said element has been made rigid.

10. The combination recited in claim 1 further comprising a stepping device including a pawl, a ratchet, and means connecting said second member to said pawl to cause said ratchet to be moved in accordance with selective operation of said mechanism.

11. The combination recited in claim 10 further comprising a settable digit representing element operatively associated with said ratchet and movable thereby in accordance with said selected operation.

12. The combination recited in claim 1 further comprising a printing device having a type carrier and means connecting said type carrier to said second member.
